UNITED STATES PATENT OFFICE.

JOHANNES RICHTER, OF NIEDERLOSSNITZ-DRESDEN, GERMANY.

STRINGED INSTRUMENT.

1,409,064.

Specification of Letters Patent.

Patented Mar. 7, 1922.

Application filed May 1, 1920. Serial No. 378,344.

To all whom it may concern:

Be it known that I, JOHANNES RICHTER, a citizen of the German Republic, and residing at Niederlossnitz-Dresden, Germany, 5 have invented certain new and useful Improvements in Stringed Instruments, of which the following is a specification.

This invention relates to improvements in stringed instruments, and more particularly 10 to an improved braking device for preventing the tensioned strings from becoming loose by an unintended return movement of the string tensioning-bolt.

In the annexed drawing:
15 Fig. 1 is a front view, and

Fig. 2 is a sectional side view, of the head of a mandolin fitted with the improved arrangement, while

Fig. 3 shows the string tensioning-bolt 20 with its braking member.

The head *a* of the stringed instrument, in the example a mandolin, is fitted with one bore for each string, which bores, for preventing the same from becoming worn, are provided 25 with a metal plate or metal plates *b* fixed on said head. Each bore serves for the reception of a string tensioning-bolt, which snugly fits therein and which comprises a metal pin having a thin front part *c* and a thicker rear 30 part *d* with an intermediary cone *e*, while in said front part *c* a cross-hole *f* for the reception of the string-end and on the end of said rear part *d* a handle *g* for turning the bolt are provided, the latter being detachably 35 fixed to the bolt by means of a cotter *h*. On said cone *e* a disc *i* is either firmly pressed thereon or integral with said cone. On the metal plate or metal plates *b*, an arc-shaped member *k*, one for each tensioning-bolt, is so 40 fulcrumed at *l* that, when the tensioning-

bolt is put in place, it can be brought in peripheral contact with the disc *i*, said arc-shaped member *k* having a length of about $\frac{1}{3}$ of the circumference of said disc. On the free downwardly pointing end of said arc-shaped member *k*, a projection *m* is provided.

The operation is as follows:— The string-end is led at an angle over the projection *m* of said arc-shaped member *k* and then wound upon the thin end *c* of the tensioning-bolt and fixed with its free end in the cross-hole *f* of the same. When tensioning the string by a rotation of the tensioning-bolt, the arc-shaped member *k* is pulled into closer contact with the periphery of the disc *i* and forms thus a kind of brake for preventing a return movement of the tensioning-bolt, whereby the string is prevented from becoming loose and permanently kept in the tensioned position, said braking action being the higher the more the string is tensioned.

What I claim, is:—

In a stringed instrument, a string tensioning-bolt, a disc on the latter, an arc-shaped member fulcrumed above said disc and in peripheral contact with the latter, a projection on the free end of said arc-shaped member, and a string-end first led at an angle over said projection, then wound upon, and finally fixed to, said tensioning-bolt, substantially as and for the purpose set forth.

In testimony whereof I have hereunto set my hand in the presence of two subscribing 75 witnesses.

JOHANNES RICHTER.
